UNITED STATES PATENT OFFICE

95,391

DESIGN FOR AN ENVELOPE HAND BAG

Ossip J. Walinsky, New York, N. Y.

Application January 5, 1935, Serial No. 54,731

Term of patent 7 years

To all whom it may concern:

Be it known that I, Ossip J. Walinsky, a citizen of the United States, and resident of New York city, Borough of Manhattan, in the county and State of New York, have invented a new, original, and ornamental Design for Envelope Hand Bags, of which the following is a specification, reference being had to the accompanying drawing, forming a part thereof, and of which Figure 1 is an isometric perspective view of an envelope handbag in closed position, and Fig. 2 is an isometric perspective view thereof in full open and expanded position, showing my new design.

The dominant features of the design consist of a handbag having side walls and an intermediate partition wall, which walls are provided with marginal frame portions along the tops and ends thereof, and a single continuous flap for the opposite sides of the handbag centrally longitudinally related to the top of the partition frame and adapted to overlie the tops of the side wall frames.

I claim:

The ornamental design for an envelope handbag substantially as shown and described.

OSSIP J. WALINSKY.
